UNITED STATES PATENT OFFICE

GEORGE W. McFARLANE, JR., OF LUFKIN, TEXAS

SEPARATOR

Application filed February 8, 1930. Serial No. 426,993.

This invention relates to a continuous flow centrifugal separator designed and adapted to separate liquids having different specific gravities.

5 Some of the objects of the present invention are: to provide a separator of the indicated character which enables the movement of the liquids at higher velocities with safety; to enable changes in the separating ratio 10 while the separator is in operation; and to enable the slip of the liquid between the paddle wheel and its housing as an aid in breaking down emulsions and colloids.

With the foregoing and other objects in 15 view, the invention resides in the particular provision, construction and operation of the parts hereinafter described and illustrated in the accompanying drawings, in which

Figure 1 is a central vertical section 20 through the separator and embodying the features of the invention;

Figure 2 is a fragmentary sectional plan view, the section being taken on the line 2—2 of Figure 1 and a portion of the distributing 25 disk being broken away to show certain features of the separator.

Referring now more particularly to the drawing it will be apparent that the separator consists of two principal units, a stationary unit 10 in the form of a housing, and a rotatable unit 11 in the form of a wheel which is mounted for rotation within the housing. The housing 10 consists of parts 12, 13 and 14. The part 12 is secured as at 30 15 to the part 13, and the part 14 is secured as at 16 to the part 13. The part 13 is of hollow construction in order to form a circular chamber 17 in conjunction with the parts 12 and 14 to receive therein the wheel 11. This 40 wheel 11 consists of parts 18, 19 and 20. The part 18 is in the form of a distributing disk provided with a central section 21 in the shape of a frustum of a cone having an opening 22 therein which communicates with a circular series of ducts or apertures 23. The part 19 is in the form of a separating disk having two sets of radial paddles 24 and 25 on its peripheral or circumferential edge. The disk 18 is equal in diameter to the circle 45 described by the outer edges of the paddles

24 and 25. The part 20 is in the form of a spreader disk and has a central enlarged circular section 26 provided with a circumferential series of ducts or apertures 27. The parts 18, 19 and 20 are bored to receive a shaft 55 28. The shaft is provided with a fixed collar 29 threaded as at 30 to receive a nut 31. The parts 18, 19 and 20 are securely clamped together between the collar 29 and the nut 31. The opposite ends of the shaft 28 are mounted 60 for rotation respectively in bearings 32 and 33 carried by the parts 12 and 14 of the housing 10. The collar 29 rests in contact with the bearing 33 to maintain the wheel 11 in proper position within the housing 10 for free 65 rotational movement. It will be apparent that the spreader disk 20 is larger in diameter than the circle described by the outer edges of the paddles 25, to present a marginal edge 34 on the disk 20 which is disposed between a depending flange 35 integral with the part 13 of the housing and the part 20 thereof. It will also be apparent that the wheel 10 in its 70 entirety is smaller than the space presented by the chamber 17 in which the wheel 11 rotates, thereby making it possible to rotate the wheel at a rapid rate of speed in order that the liquids may be moved at a high velocity. The shaft 28 may be driven in any suitable manner.

The part 12 of the housing 10 has an intake 36 at or near the center thereof which leads downwardly directly over the opening 22 in the disk 18. The part 13 of the housing has an outlet 37 at the perimeter of the wheel 11 85 slightly above the disk 20 of the wheel. The outlet 37 communicates with an annular space defined by the marginal edge 34 of the disk 20 and the depending flange 35, the lower edge of the latter being spaced from the upper surface of said marginal edge 34 to allow liquid to flow from the chamber 17 through the outlet 37. The part 14 of the housing has an outlet 38 between the perimeter and the center of the wheel 11. The outlet 37 has a control valve 39, and the outlet 38 90 has a control valve 40.

The operation of the separator is as follows:

The liquid on entering the housing 10 100

through the intake 36 is distributed by the disk 18 between the disk 18 and the disk 19 and moves outwardly until it passes the circumferential edge of the disk 19. It is then acted on by the paddles 24 in conjunction with the disk 18 which separates the liquid into streams which flow downwardly to the action of the paddles 25 in conjunction with the disk 20, the latter serving to spread the liquid. The wheel parts cause a cleavage of liquid of relatively heavy specific gravity which passes from the top of the disk 20 by centrifugal force through the outlet 37, and also cause a cleavage of liquid of relatively lighter specific gravity to flow through the apertures 27 in the disk section 26 into the outlet 38. The valves 39 and 40 may be manipulated in such a manner that the liquid may be separated in any ratio desired while the separator is in operation.

Claims:

1. In a separator of the class described, the combination of a stationary casing provided with a liquid inlet at the top thereof, and outlets which are disposed at relatively different levels, and a rotor which rotates within said casing on a vertical axis, said rotor comprising an upper liquid distributing part, an intermediate liquid separating part smaller than the distributing part, and a lower liquid spreading part larger than the separating part, to cause a cleavage of liquid of relatively heavy specific gravity to flow through the uppermost outlet and a cleavage of liquid of relatively light specific gravity to flow through the lowermost outlet.
2. In a separator of the class described, the combination of a stationary casing provided with a liquid inlet at the top thereof, and outlets which are disposed at relatively different levels, and a rotor which rotates within said casing on a vertical axis, said rotor comprising an upper part having a series of apertures therein for distributing the liquid as it enters the casing from the inlet, an intermediate part adapted to separate the liquid after it passes through said apertures, and a lower part adapted to spread the liquid coming from said intermediate part, so as to cause a cleavage of liquid of relatively heavy specific gravity to flow through the uppermost outlet and a cleavage of liquid of relatively light specific gravity to flow through the lowermost outlet.
3. In a separator of the class described, the combination of a stationary casing provided with a liquid inlet at the top thereof, and outlets which are disposed at relatively different levels, and a rotor which rotates within said casing on a vertical axis, said rotor comprising an upper part having a series of apertures therein for distributing the liquid as it enters the casing from the inlet, an intermediate disk having upper and lower sets of radial paddles on the periphery thereof, and

a lower part adapted to spread the liquid coming from said intermediate part, so as to cause a cleavage of liquid of relatively heavy specific gravity to flow through the uppermost outlet and a cleavage of liquid of relatively light specific gravity to flow through the lowermost outlet.

4. In a separator of the class described, the combination of a stationary casing provided with a liquid inlet at the top thereof, and outlets which are disposed at relatively different levels, and a rotor which rotates within said casing on a vertical axis, said rotor comprising an upper liquid distributing part, an intermediate liquid separating part, and a lower liquid spreading part, to cause a cleavage of liquid of relatively heavy specific gravity to flow through the uppermost outlet and a cleavage of liquid of relatively light specific gravity to flow through the lowermost outlet, and a control device operatively connected with each of said outlets, for the purpose of controlling the flow of liquid therethrough.

5. In a separator of the class described, the combination of a stationary casing provided with a liquid inlet at the top thereof, and outlets which are disposed at relatively different levels, and a rotor which rotates within said casing on a vertical axis, said rotor comprising three disks arranged in superposed spaced relation, there being an upper disk having apertures therein, an intermediate disk having radial paddles on the periphery thereof, and a lower disk having apertures therein, whereby the liquid on entering the casing through said inlet will be distributed by the apertures in the upper disk between the latter and the intermediate disk, separated by said paddles, spread by the lower disk and some of the liquid passing through the apertures in the lower disk, to cause a cleavage of liquid of relatively heavy specific gravity to flow through the uppermost outlet and a cleavage of relatively light specific gravity to flow through the lowermost outlet.
